PORTABLE TOILET

Bernard C. Sharp, White Plains, N.Y., assignor to Sears,
Roebuck and Co., Chicago, Ill.

Filed Sept. 25, 1972, Ser. No. 291,590

Term of patent 14 years

Int. Cl. D23—02

U.S. Cl. D23—48

Fig. 1.

Fig. 2.

FIG. 1 is a front perspective view of a portable toilet, showing my new design;

FIG. 2 is a side elevational view thereof, partly in cross-section;

FIG. 3 is an exploded rear perspective view thereof;

FIG. 4 is a fragmentary perspective view thereof; and

FIG. 5 is a fragmentary cross-sectional view taken on line 5-5 of FIG. 2.

The broken line representation of a carrying strap in FIGS. 1 through 5 is for purposes of illustration only.

I claim:

The ornamental design for a portable toilet, as shown and described.
